(57) **CLAIM**

The ornamental design for balloon shaped sign, as shown and described.

DESCRIPTION

FIG. 1 is a perspective view of a balloon shaped sign showing my new design in use with multiple signs connected to a for sale sign;

FIG. 2 is a front elevational view of the invention;

FIG. 3 is a rear elevational view of the invention;

FIG. 4 is a left-side elevational view of the invention;

FIG. 5 is a top plan view of the invention; and,

FIG. 6 is a bottom plan view of the invention.

In the drawings, the broken lines illustrate the environment in which the claimed design is used and forms no part of the claim.
